UNITED STATES PATENT OFFICE.

HOWARD L. FISCHER, OF ST. PAUL, MINNESOTA, ASSIGNOR TO BROWN & BIGELOW,
OF ST. PAUL, MINNESOTA, A CORPORATION OF MINNESOTA.

PERPETUAL MEMORANDUM PAD.

Application filed May 14, 1923. Serial No. 638,706.

To all whom it may concern:

Be it known that I, HOWARD L. FISCHER, a citizen of the United States of America, residing at St. Paul, in the county of Ramsey and State of Minnesota, have invented certain new and useful Improvements in Perpetual Memorandum Pads, of which the following is a specification.

My invention relates to a memorandum pad which is of a nature to form a means upon which a memorandum can be written and erased to leave the memorandum surface in readiness to receive another written memorandum, so that the memorandum pad is of a perpetual nature.

A feature of the invention is in providing a smooth transparent or translucent surface such as celluloid or other suitable material, which can be written upon, but which does not receive the crayon from a pencil or the ink from a pen, but is so smooth as to allow the writing instrument to slide freely over its surface. By means of this writing surface any pointed instrument can be used to write upon my memorandum pad. It is desirable that the writing surface be sufficiently flexible to transmit the pressure of the writing instrument to the members below the writing surface sheet so that the impression will be transferred in a manner to form a memorandum upon the surface which is visible through the writing surface of the pad.

The invention further includes means for providing a wax-like carbon member which has associated with it a tissue-like member or sheet which is adapted to adhere to the carbon waxed-like member when writing pressure is applied so as to provide means for clearly indicating the writing through the transparent face of the memorandum pad.

My invention includes means for holding the members associated together so that they will be held smooth and flat to prevent wrinkling or injury to the members so that the memorandum pad can be used again and again without injuring the members so that they do not properly function, as would be the case if they were not secured together in a manner as I have illustrated.

In the invention I have provided means for readily erasing any memorandum which has been written upon the pad. The eras-

ing means forms a double function in erasing the writing from the pad by separating the adherent surface of the tissue member from the carbon waxed-like member and includes means for rubbing over the surface of the waxed-like member so as to smooth the surface of the same in a manner to keep it prepared to readily receive the impression of a new memorandum after the old has been erased from the same.

In the drawings forming a part of the specification:

Figure 1 is a perspective view of my memorandum pad.

Figure 2 is a cross section along the line 2-2 of Figure 1 on an enlarged scale.

Figure 3 is a perspective similar to Figure 1 with the erasing means in a different position.

Figure 4 is an alternative form of the invention.

Figure 5 is a section on the line 5-5 of Figure 4.

Figure 6 is an enlarged detail of a portion of the memorandum pad.

In the drawings the memorandum pad A is formed with a transparent or translucent smooth writing surface 10 which may be formed of celluloid or any other suitable material. Directly beneath the member 10 is a white or other colored tissue sheet or member 11 and the member 10 is sufficiently flexible and thin enough to allow the pressure of the writing to be readily transmitted through the same to the tissue 11.

Beneath the tissue 11 I provide a waxed-like or paraffined member 12. The member 12 is of any suitable color to form a contrast with the tissue member 11 so that if the member 12 is of a dark blue or carbon-like color and the tissue member 11 is of a white nature and translucent, then when writing is applied to the surface 10 of the memorandum pad the tissue 11 will be of such a nature as to reproduce the writing by adhering to the waxed-like surface 13 of the member 12 at the point only where the writing pressure is applied.

A supporting back 14 is provided beneath the waxed-like member 12 so as to protect and support the same. This back is not especially necessary provided the member 12 is made sufficiently rigid and of a thickness to form a support in itself.

The members 10, 11, 12 and 14 are se-

cured together by the staples 15 so that they are held flat and smooth and to prevent wrinkling of the tissue 11. The transparent celluloid member 10 forms a protecting means for the tissue sheet 11 and also protects the waxed-like member 12 so that in use, even though the surface 10 is written upon with a pencil or other instrument the marks of the crayon or instrument will not be apparent on the surface 10, but pressure of the marks will be transmitted to the tissue 11 which will be impinged within the waxed-like surface of the member 12 and owing to the nature of the tissue it will be caused to adhere to the surface 13 and thus the contrast of color between the tissue sheet 11 and the carbon or waxed-like member 12 is apparent through the transparent surface of the sheet member 10.

The tissue 11 will remain in contact with the surface 13 so as to illustrate the writing until it has been separated from the waxed-like surface 13, thus the memorandum is displayed on the pad A until the tissue 11 is separated from the same.

I provide a member 16 in the form of a band, the portion 17 of which extends over the outer surface of the member 10 and the portion 18 of which extends beneath the tissue 11 and the member 12. The portion 18 of the erasing member 16 bears against the waxed-like surface 13 which is of a somewhat soft nature so as to receive the writing pressure to a certain degree. The erasing member is operated to slide back and forth over the surface 10 and over the surface 13 and forming a stripper to separate the tissue 11 from the surface 13 of the member 12. In this manner the written memorandum can be readily erased from the memorandum pad, as is clearly illustrated in Figure 3 where the erasing member is partially slid along the pad from the top of the same. After the erasing member is drawn or slid back and forth it will clear the surface of the tissue from the member 12 and prepare the pad for a new memorandum.

In operation the erasing member forms a double function by separating the tissue 11 from the surface 13 and the portion 18 of this member forms a means for rubbing over the surface 13 to tend to smoothen the same, thereby eliminating the marks caused by the writing pressure on the surface 13 and keeping this surface in readiness to receive a clear and sharp cut memorandum which is visible through the member 10.

It is an important feature of this invention to provide means for protecting the tissue 11 which is readily accomplished by the transparent member 10. In addition it is equally important to keep the tissue straight and flat against the surface of the

carbon member 12 without any wrinkles and so that the writing will be readily reproduced by the same. Then, further, the wiping of the waxed-like surface 13 by the member 16 is of equal importance to keep the memorandum pad in readiness for use and to prolong the life of the same.

The face portion of the part 17 of the erasing member 16 can be used for printed matter or other displays for various purposes.

In Figure 4 I have illustrated a perspective view of an alternative construction in which the member 16 extends about the card board or supporting back 14 with the portion 18 of the member 16 engaging against the back 14, while the portion 17 of this member extends between the tissue 11 and the carbon waxed-like member 12. In this construction the portion 17 forms the wiping means for the waxed-like member 12 and separating for erasing the writing or memorandum from the pad A. The function of the member 16 in this construction is identical to that in Figures 1 and 2, and it can be slid back and forth to erase any memorandums from the pad A.

In Figure 1 I have illustrated the memorandum namely: "Call John Doe Thursday" on the pad A, while in Figures 3 and 4 I have illustrated the erasing member 16 in the position it will assume if it is slid along the pad to erase the memorandum, these figures showing the memorandum partly erased. When the erasing member 16 is used the pad A is cleared of any writing or memorandum and is in readiness to receive writing just the same as if a new sheet of paper were brought into use.

The pad A can be made without the transparent member 10 if it is desired, in which case the pad will function exactly the same to receive a memorandum of writing, excepting that the tissue cannot be written upon with a lead pencil, crayon or other writing instrument, which would make a mark on the tissue. If the transparent member 10 is left off then it is necessary to write or engage the tissue with a smooth instrument which will not leave a writing mark on the surface of the same. The erasing member 16 will operate in the same manner without the transparent member 10 to clear the sheet for a new memorandum.

The use of a memorandum pad of this nature is very extensive and unless it is made up of a substantial nature in a manner as described the use is very limited, because when the tissue becomes injured it is not practical for use, so it is very important to have the same held in close proximity to the surface 13 and protected in a manner as illustrated in the drawings. The transparent member, together with the tissue member, must be held firm and in place above the car-

bon sheet and the surface 13 must be kept prepared with a smooth even surface so that the tissue will readily adhere when writing is applied.

5 My invention accomplishes these features and provides a memorandum pad which can be used without danger of the memorandum being erased before it is desired.

In accordance with the patent statutes I 10 have described the principles of my invention, together with the drawing adapted to illustrate the best embodiment thereof, but I desire to have it understood that I do not wish to confine my invention to the particular illustration shown in the drawings and 15 wish to protect the invention within the scope of the following claims:

I claim:

1. A memorandum pad including, a transparent sheet, a tissue sheet, a waxed-like carbon sheet, means for securing said sheets together to hold the same in close proximity and against separation at their ends and means for separating the tissue sheet from 25 the carbon sheet to erase the memorandum written upon said pad.

2. A memorandum pad including, a smooth surface for writing upon without marking with a pencil, means for reproducing the writing and means for erasing the writing from the pad by means of a stripper extending between the members adapted to reproduce the writing which separates the same.

3. A perpetual memorandum pad including, a transparent member, a tissue member, a waxed-like carbon member secured together at their ends and means for separating the tissue member from the waxed-like carbon member to erase any writing which is reproduced by writing upon the transparent member and causing the tissue member to be disengaged from the carbon member.

4. A memorandum pad including, a transparent member, a tissue member, a waxed-like member adjacent said tissue member of a color visible through said tissue member at the point where the tissue member adheres to said waxed-like member and means 50 for separating the tissue member from said waxed-like member to erase and disengage the tissue member from the waxed-like member so that the color of the waxed-like member is not visible through the tissue member.

5. A memorandum pad comprising, a tissue member, a waxed-like colored member, means for securing said tissue member and colored member together and means extending between said tissue member and waxed 60 like member to separate the adhering part

of said tissue member from said waxed-like member to erase the memorandum appearing on said tissue member.

6. A memorandum pad having means for receiving a memorandum comprising, a tissue member of a light color and a waxed-like dark colored member, means for securing said members together and an erasing member adapted to extend between the tissue and waxed-like member to separate said tissue from said waxed-like member to erase a memorandum from said pad and at the same time to polish the surface of said waxed-like member adjacent said tissue member. 75

7. A perpetual memorandum pad including, a tissue member, a waxed-like colored member, said tissue sheet being adapted to adhere to the waxed-like colored member to reproduce the writing on the tissue member 80 and means for separating the adhering portion of said tissue member to clear said memorandum pad, said means forming a wiper for said waxed-like member to prepare the surface of the same for coaction with the 85 tissue member.

8. A perpetual memorandum pad including, a transparent member, a tissue member, a waxed-like colored member, means for holding said members together, said tissue 90 member being adapted to adhere to said waxed-like member when writing is applied to said transparent member and means for separating said tissue member from said waxed-like member to erase the memorandum on said pad. 95

9. A writing and drawing pad comprising a base coated on one face with a plastic substance, a tissue-sheet superposed on said coating, the base with its coating and the tissue-sheet differing in color, said sheet being adapted upon impressure to adhere to said plastic substance along the lines of impressure, and means interposed between said base and tissue sheet operable to raise any pressed portion of the latter from the base. 100

10. A writing and drawing pad comprising a base coated on one face with a plastic substance, a tissue-sheet superposed on said coating, the base with its coating and the tissue-sheet differing in color, said sheet being adapted upon impressure to adhere to said plastic substance along the lines of impressure, a strip interposed between said base and sheet and movable longitudinally 110 thereof to raise any pressed portion of the sheet from the base, and means for guiding said strip in said longitudinal movement. 115

HOWARD L. FISCHER.
